UNITED STATES PATENT OFFICE.

EDWARD J. BROWN, OF CLEVELAND, OHIO, ASSIGNOR, BY DIRECT AND MESNE ASSIGNMENTS, OF ONE-HALF TO FRIEDERICH J. LANGER AND ONE-HALF TO RICHARD B. MOSER, BOTH OF CLEVELAND, OHIO.

FLUSHING DEVICE FOR SINKS, &c.

No. 895,955.

Specification of Letters Patent.

Patented Aug. 11, 1908.

Application filed March 6, 1907. Serial No. 360,929.

To all whom it may concern:

Be it known that I, EDWARD J. BROWN, a citizen of the United States, residing at Cleveland, in the county of Cuyahoga and State of Ohio, have invented certain new and useful Improvements in Flushing Devices for Sinks, &c., and do declare that the following is a full, clear, and exact description of the invention, which will enable others skilled in the art to which it appertains to make and use the same.

My invention relates to flushing devices for sinks and lavatory waste connections, and the invention comprises the construction and arrangement of parts substantially as hereinafter shown and described and more particularly pointed out in the claims.

In general, the object of the invention is to direct a continuous stream of water under pressure to and through the waste connections of sinks, closets, basins and the like, to the end that accumulations in the pipes and traps may be forcibly removed. In furtherance of this end, the device is constructed to hold caustic soda, soluble sulfates or other chemicals in the line of water pressure to promote disintegration and dissolution of the accumulations. The device is also particularly constructed to have a more or less universal application to varying styles of fixtures and to fit different sizes and shapes of waste openings.

In the accompanying drawings, Figure 1 is a sectional view centrally of the device and of a lavatory basin, and shows the working relation of the device to the waste opening. Figs. 2, 3, 4 and 5 are sectional views in perspective of the lower device parts and represent the main receptacle, the middle flexible ring, the nozzle member, and the nozzle ring, respectively. Fig. 6 is a sectional view of a closet bowl and of the device as applied thereto. Fig. 7 is a sectional view of a sink with a part of the device mounted over a fairly large waste opening therein. Figs. 8 and 9 are perspective views of the device in two parts showing the cover removed and above the main body for the introduction of chemicals or disinfectants.

The device consists of a number of separable parts which combine to make a unitary and divisible apparatus applicable to varying needs and conditions wherever waste

connections are found. Thus, at the top of the device is a handle 2 having a vertical water passage —3— at one side terminating at its upper end in a laterally inclined elbow —4— threaded internally to receive a hose connection —5—, and having an extension —6— at its bottom adapted to screw into a threaded opening —7— located at one side of the center of hollow cap or cover —8— removably mounted upon main body —12. Cover —8— is circular in outline and handle —2— is centrally disposed above the same and in respect to the device as a whole so that whatever pressure brought to bear thereon by hand is uniformly distributed to make effective sealing wherever the device may be applied. A curved leg —9— forms part of handle —2— and bears upon cover —8— diametrically opposite tubular portion —6— and thereby relieves the strain upon the threaded connection between the handle and said cover, as well as distributing the pressure equally to opposite sides of the cover.

A flanged seat —10— at the bottom edge of the cover —8— is adapted to hold a rubber or other suitable gasket —11 which serves the primary purpose of a seal between the cover and main body —12—. In reality, said body is a mixing receptacle for the fluid and for the chemicals which are placed therein and for which latter purpose said cover —8— is made removable. But cover —8— and its parts have a further utility in that they may be used in their entirety as a divisible part of the device to meet certain conditions such as found in sinks having large waste openings. Thus, in Fig. 7 a sink —A— is shown having a flat bottom —a— with a large waste opening therein leading to sewer and trap connection —a'—, and cover —8— is mounted over the waste opening with gasket —11— acting as a seal between the cover and bottom —a— of the sink. Hose connection —5— is shown in this view as attached to faucet —a²— on the water pressure line, and whatever chemicals are used may be placed within hollow cover —8— before applying the cover to the waste opening.

Now returning to the device as a whole, the upper edge of body —12— is seen to extend slightly into cover —8— and has an outer annular flange —14— against which

gasket —11— is adapted to bear. Body —12— tapers to a smaller diameter at its bottom end and has an open bottom —15— through which tubular extension —16— of nozzle member —17— is adapted to project and make a fairly close fit. An outer flange or seat —18— is cast upon nozzle member —17— and a flat flexible ring —19— of rubber or felt is mounted between the bottom edge of body —12— and said flange to seal the joint between the parts and to act in a further capacity as a sealing head for the device when used to close waste openings in closet bowls and as illustrated in Fig. 6 where the bowl is represented by —B— and waste outlet by —b—. Ring —19— must be of fairly large diameter to meet conditions like this, and must moreover, extend outward all around the device so that a certain amount of flexibility may be obtained to crowd it in place as shown. A great measure of adaptability to varying shapes and sizes of bowl openings is obtainable by a sealing ring thus placed and provided, and different sizes and shapes of rings may be used because it is removably mounted upon —12—.

Nozzle member —17— is of a reduced diameter as compared to body —12— to give room for change of position of the device in crowded places and has a perforated or grid-like end —20 through which the water has final discharge. A rubber ring —21— is seated in a groove —22— at the outer or bottom extremity of nozzle member —17— and encircles the water outlets and has a depth relatively much greater than its thickness, say about three to one, so that it may be readily compressed and fit irregular surfaces, and said ring provides a small sealing head or member which is especially adapted for use with basin or bath wastes, and which when it is applied rests as shown in Fig. 1 where the basin is represented by —C— and its waste and trap connection by —c—. Hose —5— is also herein shown as connected to a faucet —c'— of the water supply.

Now having described the main elements of the device and their advantages in use, it will be noted finally that the nozzle member —17—, ring —19—, receptacle body —12—, gasket —11— and cover —8— are separably united by means of a central tie rod —23— having a head —24— seated within grid end —20—. Rod 23 extends upward through the device and through a central opening —27— in cover —8— where it is engaged by a thumbscrew —25— adapted to seat upon the cover and draw and hold said parts together. A small plug or screw —26— (see Fig. 7) may be used to close opening —27— if rod 23 is removed.

A swirling action of the water in passing through the device is obtained by reason of the off-center intake passage —6— and the centrally arranged outlet at the bottom of

the device, and mixing of the water and chemicals is further induced by having nozzle extension —16— act as a check to immediate outflow.

What I claim, is

1. A flushing device adapted to direct a stream of liquid through waste connections and having a plurality of sealing members of varying sizes separated one from the other and adapted to fit different sized waste openings, and means to secure each of said members in place thereon apart from the other members. 70

2. A flushing device adapted to be applied to waste openings comprising a receptacle having intake and outlet openings and provided with a sealing member projecting axially at its bottom and a sealing ring projecting laterally at its sides, and means to removably secure said ring in place. 80

3. A flushing device comprised of a number of separable parts combining to make a unitary and divisible apparatus adapted to direct liquid under pressure through waste connections and having a plurality of sealing members applicable to different waste openings and comprising a sink sealing member removably supported at the top of said device, a laterally projecting closet sealing ring supported upon the sides of the device, and a downwardly projecting sealing member of lesser diameter than said other members at the bottom of said device. 90

4. A flushing device embodying a water receptacle having a removable cover and gasket therefor, in combination with a nozzle outlet at the bottom of said receptacle having a sealing ring projecting downwardly therefrom, and a central tie rod detachably connecting said parts. 100

5. In flushing devices for waste connections, a hollow body having a cover with an off-center intake, combined with a removable nozzle member at the bottom of said body and a sealing member supported thereby, and means to secure said parts together. 110

6. In flushing devices for waste connections, a receptacle having liquid intake connections and a removable outlet nozzle, a removable laterally projecting sealing member between said nozzle and receptacle, and a sealing ring at the bottom end of said nozzle. 115

7. A separable device adapted to flush waste connections and having water intake connections and comprising a main body and a removable cover therefor, a gasket for said cover and a removable nozzle at the bottom of said body, a sealing ring between said body and nozzle, a sealing member at the bottom of said nozzle, and means to separably unite said parts. 120

8. A flushing device comprising a cylindrical main body having water connections, said body having a nozzle member at its bottom of lesser diameter than said main body, 130

and said nozzle member having sealing rings projecting therefrom at both sides and bottom.

9. A transportable device adapted to direct 5 a stream of liquid through waste connections and provided with three separated sealing members mounted singly thereon and being of varying sizes and forms to fit varying sized waste openings.

10 10. A flushing device having a sealing member adapted to close waste openings and said device constructed with a separable body adapted to secure said sealing member in place, and a central tie rod separably unit- 15 ing said body parts.

11. A flushing device comprising a main receptacle having a tubular portion extending into said receptacle at its bottom apart from the main walls, and a sealing member 20 mounted at the bottom of said tubular portion.

12. A transportable device adapted to direct a stream of liquid through waste connections and provided with separate sealing 25 members mounted apart from each other at different elevations thereon, said sealing members being of varying sizes and shapes to fit singly over different kinds of waste openings.

30 13. A transportable device adapted to di-

rect a stream of liquid through waste connections and having three sealing members of different shapes separately secured upon said device apart from each other and one above the other and each adapted to fit a different 35 sized waste opening.

14. In a flushing device, a receptacle having a water intake, a removable nozzle member for said receptacle having an annular extension projecting into said receptacle apart 40 from the walls thereof and forming a channel therein, and a sealing ring at the bottom of said nozzle member.

15. A flushing member having an open bottom and a sealing ring about the same, in 45 combination with a handle removably secured upon said member at one side of its axial center and having a water passage therethrough and a transverse hand grip at its top on the axial center of said member 50 and a side portion adapted to bear down upon said member to relieve the side strain upon the handle connections.

In testimony whereof I sign this specification in the presence of two witnesses.

EDWARD J. BROWN.
